ELECTRICAL COUPLING SYSTEM

Application filed March 16, 1928. Serial No. 262,252.

Our invention relates to a method of varying the coupling between two electrical circuits and is particularly applicable to circuits operating at radio frequencies.

5 One object of our invention is to provide a suitable gain control or volume control for a receiver employing alternating current as a cathode heating source, in which case the usual filament rheostat cannot be conveniently 10 used owing to the introduction of a modulation hum.

Another object is to produce a coupling device in which the coupling may be brought to zero notwithstanding stray electrostatic 15 effects these latter being often markedly present at the higher frequencies.

Referring to the drawings, Fig. 1 shows schematically one embodiment of our invention employing a capacity reactance as the 20 control member.

Fig. 2 shows an improved embodiment of Fig. 1 in which the effect of electrostatic transfer of energy is reduced to practically zero.

25 Fig. 3 shows another form of our device in which the control impedance may be either pure or complex.

Fig. 4 shows a generalization of our bridge coupling device except that direct instead of inductive coupling is used.

30 Fig. 5 shows still another form of our variable coupling.

Referring to Fig. 1, 9 and 10 are the input connections and 11 and 12 the output terminals. 35 L_1 and L_2 are the primary windings and have the same mutual inductance with L_3 , the secondary, but in the opposite sense or phase. C_1 and C_2 are condensers which may be equal in capacity at one point of adjustment of the variable C_1 , or both may vary simultaneously but in opposite directions (not shown) and when thus operated, would have a position of adjustment in which their capacitance would be equal.

40 In operation, when the condensers C_1 and

C_2 are of equal capacity, currents of equal magnitude and phase will flow through the inductances L_1 and L_2 and as these windings are of opposite "sense" no voltage will be induced in secondary L_3 .

When, however, C_1 and C_2 are of different values of capacity currents of different magnitude and phase flow through the inductances L_1 and L_2 and a voltage is therefore induced in L_3 . The magnitude of this voltage may be varied by varying C_1 from zero which may be the position of maximum gain to a value almost equal to the capacity of C_2 the position of minimum gain.

55 In reference to Fig. 2, in high frequency 60 circuits an electrostatic coupling may prevent an exact zero being reached. An electrostatic shield between L_1 , L_2 , and L_3 in Fig. 1 will correct this. However, unless executed in an extremely careful manner it may increase the 65 losses in the circuit. The method shown in Fig. 2 will prevent this effect, is inexpensive and introduces no appreciable losses.

In Fig. 2, 9' and 10' are the input leads and 11' and 12' are the output terminals. C_1' is 70 the controlling condenser and C_2' the equivalent of C_2 Fig. 1. L_3' is the equivalent of L_3 Fig. 1. The two primaries 15 and 16 have their corresponding convolutions adjacent, but, as will be seen, are connected in the 75 circuit so that at any given moment the current in each is of the opposite sense. It will be seen that this method of winding insures extremely close coupling between the two primary coils, and when the bridge is 80 balanced equal currents flow through the two coils in opposite directions and on account of this almost perfect coupling no appreciable magnetic field is set up, which, of course, means there is practically no voltage 85 drop across the coils and no electrostatic field is set up, and therefore there is substantially no electrostatic coupling to L_3' the secondary.

90 Fig. 3 shows a generalization of our bridge

coupling device. Z_1 Z_2 are two impedances having a point of common value and may be pure or complex. Z_1 is indicated as variable but it is obvious that both may be so. L_1' and L_2' are the primaries coupled equally but in opposite sense to the secondary L_3' . The condition for zero coupling is, when L_1' and L_2' are equal to one another and equally coupled to L_3' , that Z_1 shall equal Z_2 .

10 Fig. 4 shows a generalization of our bridge coupling device except that direct method of coupling is used. The input leads may be 9_1 and 10_1 and the output leads 11_1 and 12_1 but it should be understood that all these circuits 15 are reversible in this respect. In this variation the expression of zero coupling is equal to

$$\frac{Z_1}{Z_2} = \frac{Z_1'}{Z_2'}$$

20 Fig. 5 shows a form in which the control impedances are in parallel with the coupling inductances.

The system shown in Fig. 2 is especially 25 applicable as a gain control for radio frequency amplifiers using alternating current as a cathode heating source. An enormous range of control is necessary in the modern radio receiver as the received energy in the 30 antenna circuit may vary several hundred thousand to one between the powerful local station a few blocks away and a station a thousand miles or more away of moderate power. For this reason a minimum of energy transfer which should closely approach 35 zero should be obtainable under the conditions of great received power in the antenna. On the other hand a maximum transfer from the antenna to the following circuits should also be obtainable to make the receiver capable of satisfactory distant reception. It should also be noted that the decreased 40 coupling, which would normally be used for local reception in a large metropolis having a considerable number of high power stations automatically increases the selectivity of the receiver.

As is well known the usual gain control for a radio frequency amplifier, the cathodes 45 of whose tubes are operating on direct current, is a rheostat in the cathode circuit for reducing the cathode heat, and hence the emission. This method is thoroughly impractical when the cathodes are heated from an alternating current source, due to the fact that if the cathode heat is reduced to anything like the point needed for the lower 50 ranges of sensitivity the cathode will cease to emit at all during the lower voltage values of the alternating current, hence modulating the carrier wave and its side bands and causing upon demodulation an unpleasant audio frequency hum.

55 It should be understood that it is immate-

rial whether one control-impedance is varied or if both are varied oppositely.

Another advantage of our variable coupling device when used as a gain control for a radio receiver is that it will prevent the 70 grid of the first radio frequency tube from going positive as a result of strong local signals, and thus causing modulations of signals of other frequencies.

In the above specification we have rather 75 laid stress upon the application of our device to radio telephonic circuits. There are many other uses to which this device may be put. Therefore, we do not wish to be limited to the exact embodiment shown, except in so far 80 as we are limited by claims when allowed.

We claim:

1. A gain control for a radio receiver including an input and an output circuit so connected in respect to the mechanisms of 85 said receiver that substantially all the signal energy must pass into said input circuit and be delivered by said output circuit, said input circuit comprising two parallel branches, each of said branches consisting of an inductance and a capacitance in series, each of said inductances being equal and fixed and at least one of said capacitances being available over a range of values such that the two capacitances can be made electrically equal to one 90 another, and said output circuit comprising a third inductance coupled equally to each of the aforesaid inductances in the parallel branches, but having opposite inductive relationships with each of the branch inductances respectively.

2. A variable coupling device capable of allowing energy transfer between two electrical circuits extending from a given maximum down to and including a substantial 100 zero degree of energy transfer, including one electrical circuit comprising a single inductance coil, and another electrical circuit comprising an inductance coil with two substantially identical parallel windings having the 105 maximum feasible physical juxtaposition so that equal and opposite currents therethrough shall produce substantially a zero electrical field thereabouts, said first coil bearing such physical relationship to said 110 second coil that the former shall lie substantially within each and every electrical field produced by the latter, and said second coil having in series with each of its windings a capacity, at least one of said capacities being 115 variable over a range including the value of the other capacity, the two branch circuits comprised by each winding and the capacity connected thereunto being so connected to one another and in such respect to the energy 120 flowing therein that the fields of these respective windings shall be in opposition to one another.

3. The method of securing a readily variable degree of coupling, including a virtually 125

zero electro-magnetic and electro-static coupling between two coils, which includes winding one coil with at least two physically juxtaposed and substantially identical windings, each in a branch circuit comprising said winding and a capacity, at least one of said capacities in the branch circuits being so variable that the values of the several capacities may have a ratio of unity and may be made to vary from such unity ratio to a desired degree.
